UNITED STATES PATENT OFFICE.

FRANK H. JOHNSTON, OF CHICAGO, ILLINOIS, ASSIGNOR TO ACME CARD SYSTEM COMPANY, OF CHICAGO, ILLINOIS, A CORPORATION OF SOUTH DAKOTA.

CARD-PROTECTOR.

1,354,616.

Specification of Letters Patent.

Patented Oct. 5, 1920.

Application filed November 19, 1919. Serial No. 339,250.

To all whom it may concern:

Be it known that I, FRANK H. JOHNSTON, a citizen of the United States, residing in the city of Chicago, county of Cook, and 5 State of Illinois, have invented certain new and useful Improvements in Card-Protectors, of which the following is a specification.

My invention relates to improvements in 10 card indexes and refers more particularly to a transparent protector for index cards. It has among its salient objects to provide a plurality of transparent card shaped protectors for the exposed portions of index cards; to provide a plurality of sheets of celluloid, pyrolin or like substance suspended or fitted to the index card holder, similar to the index cards or in any convenient manner, said protectors arranged to 15 cover the exposed surfaces of the index cards; to provide a plurality of transparent, protecting members adapted to lie flat with the cards and made of material that is difficult to tear and will withstand the constant 20 usage given index cards; to provide protectors of different colors and so arranged that all of the exposed edges of the under cards are protected from wear and dirt at 25 all times; to provide transparent protectors that occupy no more space in the holder than an index card and at the same time make the index cards more accessible than when using a single protector covering all 30 of the cards; to provide a simple, inexpensive card protector which can be removed at any time and in general to provide a protector of the character referred to.

In the drawings:

Figure 1 is a plan view of the index card holder with three colored protectors thereon. Fig. 2 is an edge view of the index card holder shown in Fig. 1.

Fig. 3 is a fragmentary detail showing 45 means of suspending protector members.

Referring in detail to the drawings, 1 is a common type of index card holder having lateral channels 2 in which are set resilient wire hangers 3. To these hangers are suspended index cards 4 by means of 50 clips 5. The holders are adapted to lie flat in a horizontal position or swing vertically in a suitable stand (not shown) by means of pivot rods 6.

The protector members 7 are similarly suspended to the wire hangers by means of 55 clips 5^a as are the index cards 4. Also the protectors are suspended upon the same wire hangers with one of the index cards, thereby obviating the necessity of having a special hanger for the protector. 60

In Fig. 2 is shown more clearly the manner in which the protectors overlap to cover the exposed portions of the cards. By the use of a plurality of protectors, it is not necessary to uncover all of the cards to 65 make a single entry. The use of colored protectors serves to identify certain or related cards, which may be placed under the same color, or assist in showing more plainly the area covered by the respective 70 protectors.

It is not my purpose to limit myself to the use of card protectors of this sort mounted on this type of holder for these protectors can be as readily mounted and serve identi- 75 cally the same purpose on practically any system where overlapping index cards are used.

I claim as my invention:

1. In index card protectors, the combination with an index card holder, of a plurality of overlapping transparent protector members covering exposed portions of the index cards. 80

2. In index card protectors, the combination with an index card holder, of a plurality of transparent protector members arranged at intervals between index cards, the lower end of said protector members elongated to cover exposed portions of in- 90 dex cards. 85

3. In index card protectors, the combination with an index card holder, of a plurality of card shaped transparent, protector members arranged in overlapping relation at intervals between the indexed cards and adapted to overlap to cover exposed portions of the index cards. 95

4. In index card protectors, the combination with an index card holder, of a plurality of card shaped transparent, vari-colored protector members arranged in overlapping relation at intervals between the indexed cards and adapted to overlap to cover exposed portions of the index cards. 100

FRANK H. JOHNSTON.
